UNITED STATES PATENT OFFICE.

JAMES W. BRYCE, OF BINGHAMTON, NEW YORK, ASSIGNOR TO THE INTERNATIONAL TIME RECORDING COMPANY OF NEW YORK, A CORPORATION OF NEW YORK.

MULTIPLE TIME RECORDER.

Application filed June 23, 1921. Serial No. 479,753.

To all whom it may concern:

Be it known that I, JAMES W. BRYCE, a citizen of the United States, residing at Binghamton, in the county of Broome and State of New York, have invented certain new and useful Improvements in Multiple Time Recorders, of which the following is a full, clear, and exact description.

In many industrial plants at the present time, it is customary to keep records of the time which workmen spend on a job, in order to determine the pay at so much per hour to which he is entitled for his work. Usually the periods of elapsed time are recorded automatically on a card by a suitable machine into which the card is inserted at the beginning and at the end of a job, but under present practice a card is required for each job and for each period of a working day. This means may require a very large number of cards, and is expensive for that reason besides involving complications and adding to the amount of clerical work which has to be performed in making the computations.

The purpose I have in view in the invention upon which this application for Letters Patent is based, is to simplify this method by reducing to minimum the number of cards required and the number of computations that must be made and with this object in view I have devised what I term a multiple recorder which permits a plurality of elapsed times on different jobs to be recorded on the same card and which totalizes the several elapsed times and thereby simplifies the entire operation and reduces the number both of cards needed and computations required.

In carrying out this invention I have found it necessary for practical reasons to select a certain time unit, which for all ordinary conditions of work and practice may be the tenth of an hour or six minutes. This, therefore, is the smallest fraction of time which the machines will register or take account of, but it will be understood that this is purely arbitrary. The machine constructed on this plan, however, will register hours and tenths of an hour in elapsed time, and as the improvement over and beyond the above statement of function involves only mechanical elements most of which are well

known in the art, an understanding of its construction and mode of operation may most readily be obtained from a detailed description of the drawings hereto annexed which illustrate the same.

Fig. 1 is a view in elevation of the interior mechanism of a complete machine, the view being a vertical section on the line 1-1 of Fig. 6.

Fig. 2 is a vertical section of the same on line 2-2 of Fig. 6 looking to the left.

Fig. 3 is a vertical section on the line 3-3 of Fig. 6, looking in the same direction.

Fig. 4 is a vertical section on the line 4-4 of Fig. 6, looking to the right.

Fig. 5 is a horizontal section on the line 5-5 of Fig. 6, looking in the direction of the arrows in that figure.

Fig. 6 is a horizontal section on the line 6-6 of Fig. 2, looking down.

Fig. 7 is an enlarged detail view chiefly in elevation of the type wheel operating mechanism.

Fig. 8 is a view of the same on the same scale at right angles to Fig. 7.

Fig. 9 is another view of the same parts, this being a plan view looking down.

Fig. 10 is a plan view on an enlarged scale of a visual indicator forming part of the apparatus.

Fig. 11 is a sectional view of this part or device on the line 11-11 of Fig. 10.

Fig. 12 is a sectional view of the same on the line 12-12 of Fig. 10.

Fig. 13 is a sectional view of the same on the line 13-13 of Fig. 10.

Fig. 14 is a sectional view of the same on the line 14-14 of Fig. 13.

Fig. 15 is a side view in elevation of the device of Fig. 10.

Fig. 16 is a sectional detail on the line 16-16 of Fig. 15.

Fig. 17 is a detached view of a circuit controlling device shown in its operative relation to the machine in Fig. 2.

Fig. 18 is a section of the same on the line 18-18 of Fig. 17.

Figs. 19, 20, 21, 22, 23 and 24 illustrate details of the mechanism which will be hereinafter more fully described.

Fig. 25 is a view of one of the cards used in the machine, and

Fig. 26 is a wiring diagram of the system.

Numerals are used to designate the various parts and corresponding parts in the various figures are similarly numbered.

For a more ready understanding of the principle of the invention, reference may first be had to the card 1 shown in Fig. 25. For convenience, it is assumed that this card 10 is inserted in the machine by an employee at the beginning of a working day and punched by the operation of the handle of the machine. A knife or cutter operates to cut off a rectangular section 2 from the lower 15 left hand corner of the card which is arrested in proper position by a fixed stop, and punches two holes 3 and 4, at the starting or zero line. After the workman has finished this job, he again inserts the card and 20 operates the handle. Another section 5 is cut from the edge as the first cut allows the card to pass further into the machine and two or more holes 6 and 7 are punched.

In the meantime the clock mechanism has 25 been running and the machine controlled by such mechanisms turns the type wheels so that they print at the edge of the card 2.1 which indicates that the elapsed time on the particular job is two hours and one tenth 30 of an hour.

Suppose that the workman immediately starts on another job, at the finish of which he again inserts the card and punches two holes 8 and 9, and cuts off another section. 35 The mechanism then prints the numerals 1.9, showing the elapsed time for the job to have been one hour and nine-tenths of an hour, or, making for the present a mental calculation, four hours from the time represented by the position of the first two holes 3 and 4. This fact is shown by the two holes 8 and 9, the first of which representing tenths of an hour is on the zero line, while the hole 9 representing hours is on the fifth 45 vertical line.

We assume that this brings us to the lunch or noon hour. On returning from lunch the workman starts in on another job and again punches his card, but the two holes 10 and 50 11 will be exactly in the same position as holes 8 and 9, because the master clock has cut off the timing and other mechanism during the non-working or noon hour.

At the completion of the job the card is 55 again punched. The figures 0.8 are printed in the margin, showing that the elapsed time job was eight tenths of an hour and the holes 12 and 13 will be in positions that indicate four hours and eight tenths of an hour after the starting time indicated by holes 3 and 4.

The workman may in this way record 60 elapsed time of one or more or no other jobs, the elapsed time of each job being printed 65 in the margin while the holes by their posi-

tion will indicate the total time from the start. At the end of the day, or at any other time the total of all the elapsed times may be automatically ascertained and printed by means which will be hereinafter described, 70 but the above will show the purpose and the result of the operation of the machine.

Following, for purpose of more ready description, the method of using or operating the machine as far as practicable, a card 1 75 is inserted in the chute 14 and passes down until it encounters a stop 16 in a knife 15 (see Figs. 5 and 19), which knife is forced forward by the operation of the handle 17, Fig. 1. This handle is fast to a shaft 18 80 which carries operative cams, one of which 19, Fig. 19, engages a stud on a pivoted lever 20, the end of which engages with the bifurcated end of a pivoted bell crank lever 21, that forces an arm 22, pivoted at 23, against 85 the knife 15 and causes the latter to cut out a section from the lower left hand corner of the card.

The handle 17 carries a segmental plate 24, which has connected with its lower end a stout spiral spring 25 and is provided with teeth 26, which engage with a full stroke pawl 27 having a retractile spring 28, and which operates to prevent the backward movement of the plate 24 and the handle in 90 either direction until a full stroke or swing of the handle has been made.

By the rotary movement of the shaft 18 a cam projection 29 (Fig. 12) is caused to engage with a roller on a bell crank lever 30 100 pivoted at 31, and the upper end of this lever is connected by a link 32 with a sliding frame 33 carrying two pin barrels 34 and 35, Figs. 2 and 6, and when operated by the cam forces this frame to the left, 105 Fig. 2. Each barrel carries ten pins evenly spaced, as shown in Fig. 6, and the lower barrel, the pins on which correspond to tenths of an hour, is rotated step by step by means of a pawl 36, Fig. 15, pivoted to an 110 arm 37 fast to a spindle 38, and carrying a segmental gear 39 engaging with a similar segment 40 on a pivoted armature lever 41. The said armature lever is attracted once every six minutes by an electro-magnet 42 operated by a master clock, which is not shown, and hence the ratchet wheel 43, connected with the lower pin barrel, makes one complete revolution every hour, as such 115 ratchet wheel has ten teeth.

Motion from the lower to the upper pin barrel is imparted by the means shown in Fig. 15. The spindle of the ratchet wheel carries a cam 44 with a single projection, and on this cam bears a pawl 45, fixed on a stub shaft 45^a, bearing in plate 45^b. Also fixed on this shaft is an arm 45^c carrying a pawl 46 cooperating with ratchet 48. A spring 45^d stretched between a portion 46^a of pawl 46 and a portion 45^e of arm 45^c 120

holds said pawl resiliently against the ratchet. The pawl 45 drops once during each revolution of the ratchet 43. This movement permits the pawl 46 which has been raised and forced back by the high point of the cam 44 to be drawn forward by a spring 47 and to advance the ratchet wheel 48 and the upper pin barrel one tooth each hour. The movement of the ratchets 43 and 48 is imparted to the upper end and lower pin barrels respectively by means of flexible and extensible spindles 49^a, Fig. 16.

From the above it will be seen that the position of the pin barrels is dependent upon clock time. When, therefore, the handle is pulled the particular pins set by time will operate one or another of two horizontal lines of punches 49 and 50, and force the same through the card which is then in the chute. The punches 49 lie directly in the path of the advancing pins, and are forced forward thereby. The pins of the lower barrel, however, encounter slides 51, having upright projections 52 that engage the punches of the lower row, and in order to insure the proper return of the punches, a slide 53 is pivoted to the frame 33 and connected to a universal bar 54, which engages the punches when the frame is drawn back and pulls back those that have been advanced.

In the top of the machine is a window 55, under which are placed two disks 56, 57, with ten evenly spaced digits thereon representing hours and tenths of an hour. The tenths of an hour disk 56 is rotated step by step by the armature lever 41 operating through a pawl 58 on a ratchet wheel 59, and by any well known form of transfer mechanism 59^a one complete revolution of the said disk moves the other or hour disk 57 forward one step or one tenth of a revolution.

Each disk 56 and 57 carries a contact 60, which following its movement of rotation sweeps at one end a circular contact 61 and at the other over a series of ten contacts 62 on a sunflower, shown in Fig. 11. The purpose of this will be more fully herein-after described.

The first or mechanical operation of punching a card at the beginning of a job has now been described. Following our original assumption that the workman started in within six minutes of the beginning of a working day, it is manifest that the pin barrels will be in zero position, and the type wheels 63 which lie in front of a card in the chute and are struck by a printing pad 64 when the handle is pulled, will also be in zero position, and hence the card will come from the machine with only the two holes 3 and 4, and the figures 0.0 printed in the corresponding margin to the right. Any proper or well known

means for operating the printing pad may be employed. I have shown in Fig. 4 an arm 99 on the shaft carrying the printing pad and to this arm is connected one arm of a bell crank lever 100 by a link 101. When 70 the handle shaft is turned the bell crank-lever 100 is operated by a cam 102 on the handle shaft and pulls down the arm 99 and operates the printing mechanism.

Assume, however, that at the completion 75 of the job the card is again inserted and the handle pulled. Then the following operations will take place. The time which has elapsed since the beginning of the working day will be shown on the dials through 80 the window 55 and the pin barrels will have been moved to corresponding positions, or, following the illustration selected by the card of Fig. 25, the barrel 35 will have made two 85 and one tenth revolutions while the barrel 34 will have made two tenths of one revolution. By this means the contact 60 of the dial 56 will have been brought upon the second contact of the sunflower which corresponds to one tenth of an hour, while that of the dial 57 will rest upon the third contact or that corresponding to two hours. The pulling of the handle will hence punch the holes 6 and 7.

On the shaft 18 of the handle are toothed segments 65 that gear with other segments 66 turning about center 67 (Figs. 3 and 7) and operating arms 68 connected by spiral springs closely with segmental arms 69, turning also about the center 67. The arms 69 gear with flat plates 70 having teeth on both edges and vertically movable upon guide pins 71, entering slots 72. Parallel with these plates 70 are other plates 73, similarly adapted to have a limited vertical movement and with teeth on one edge only. Between these two bars are pinions 74 carried by intermediate vertically movable plates 75 having teeth which engage with pinions on the two type wheels 63, respectively. Pivotal connected to the intermediate bar 75 is a lever 76 turning about the shaft or center 31 and operated by a bell crank lever 77 having a stud adapted to be engaged and worked by a cam 78 on the handle shaft.

With the parts in the normal position shown in Fig. 7, operation of the machine handle to turn shaft 18 counterclockwise causes segment 69 to raise rack 70 until the latter is stopped by pawl 114. At the same time, cam 78, through levers 77, 77^a releases arm 76 so that the latter is lowered by its spring 76^a and carries pinion 74 and rack 75 with it. The rising of rack 70 and the lowering of rack 75 both operate through pinion 74 to lower the rack 73 until the latter is stopped by pawl 117. The distance through which rack 70 rises and the distance through which rack 73 descends de-

termine the position to which rack 75 shall rise or descend. This in turn, controls the setting of the type 63.

Restoration of the handle causes rack 70 to be restored to its lower position. It also causes arm 77^a to raise arm 76 with rack 75. These two operations in turn, through pinion 74, raise rack 73 to normal position, and the parts are all in the position of Fig. 7. This mechanism constitutes a well known form of differential for setting the type wheels and is controlled by the following means.

When the handle is pulled a cam 79 on its shaft (see Figs. 2 and 18) operates a bell crank lever 80 turning on shaft 31 and causes it to raise a link 81 and thereby turn a segmental gear 82 and revolve the contact arms 83, 84^a. The arm 83 is provided at one end with a brush 83^b cooperating with a contact 83^c (see Figs. 17 and 18). Integral with brush 83^b is another brush 83^d cooperating with a series of contacts 85. The other end of said arm has similar brushes 83^e, 83^f cooperating with contact 83^g and contacts 86 respectively. Arm 84^a has a similar set of contacts cooperating with contacts 84^e, 85^a at one end and 84^g, 86^a at the other end.

In the bottom of the machine are 5 rows of contacts divided into 2 groups, see Figs. 3 and 24. The contacts in the 5 rows of one group are designated 87, 88, 89, 90 and 91 and those in the other group 87^a, 88^a, 89^a, 90^a and 91^a, see also wiring diagram, Fig. 26. Of these rows 87, 89, 91 and 87^a, 89^a, 91^a are stationary and the contacts 88, 90 and 88^a, 90^a are movable, by the rocking of member 124, from engagement with the contacts on their left to engagement with the contacts on their right as viewed in Fig. 3.

In the upper left hand corner of Fig. 2 are shown pivotally mounted spring pins 92 and 93, there being ten of each which when operated bear against a card or pass through punched holes in the card where such occur to make contact with a plate 94, back of the card (see Fig. 5). At the lower left hand corner of Fig. 2 are shown two rows of ten similarly constructed and mounted pins 95 and 96, which are adapted to perform the same operation as the upper pins.

Referring now to the diagram Fig. 26, the pins 93 which correspond to hours are connected separately by insulated wires in a cable 97 to one group of the stationary contacts 89, while the other set of pins 92 corresponding to tenths of hours are similarly connected by wires in a cable 98 to the other group of stationary contacts in the same line 89^a.

The ten stationary contacts of the sunflower, Fig. 11, corresponding to and connected with the hour dial 57, are in the same

manner connected with the ten stationary contacts of one group 87, while the ten contacts of the sunflower corresponding to tenths of an hour and connected with the dial 56, are in the same way connected with the other group of ten stationary contacts in the same line 87^a. The movable contacts of one group 88 are connected with the ten contacts 86 of one of the circuit selectors 84; for example, those on the right, while the ten movable contacts of the other group in the same line 88^a are connected to the right-hand contacts 86^a of the other circuit selector 84^a. Again, the movable contacts of one group 90 are connected to the left hand contacts 85 of the first circuit selector 84, while the other and corresponding group of movable contacts 90^a are connected to the left hand group of contacts 85^a of circuit selector 84^a.

Finally, the stationary contacts of one group 91 are connected to the hour pins 95, while the other group of stationary contacts 91^a are connected with the tenths of hour pins 96. The purpose of these connections will now be described.

It has been shown that as the dials 56 and 57 are rotated by impulses from the master clock, the contacts of the two sunflowers connected therewith are caused to sweep over contacts 62. And it may now be assumed that the card is inserted at the end of the first job or two hours and one tenth of an hour after the start and the handle worked. In the manner above described the two holes 6 and 7 will be punched, but by the operation of the handle a lever 103 will be engaged by a cam 104 on shaft 18, and the other end of this lever will be forced up and toward the right in Fig. 4. The said lever is connected to a bar 105 which is also pivoted to a pivoted arm 106, so as to have a parallel motion. The bar 105, upon being forced to the right, swings an arm 107, fixed on the shaft 132^a (Fig. 2) which carries the two sets of pin arms 92 and 93, and this motion of the shaft swings the pins against the card and through the holes 3 and 4 therein so as to make contact with the plate 94.

The plate 94 (see Fig. 26) is connected by the wire 108 with one pole of a battery or source of current 109, so that current passes therefrom to the first or zero pin of the upper row 93, and thence to the first of the row of contacts 89, thence to the corresponding contact 90, and thence to the zero contact 85 of the circuit selector 84. At the same time the zero pin 92 makes contact with plate 94, so that current also flows therefrom to the zero pin of the set 92, thence to the zero stationary contact 89^a and thence through the corresponding contact 90^a to the zero contact 85^a of the circuit selector 84^a.

At this time, current is also led by wire 130

108 to the common return plate 61 of the hour sunflower and thence through the contact 60 to the stationary terminal 62 corresponding to the second hour, and thence 5 to the corresponding fixed terminal of the group 87, thence to the corresponding terminal of the right hand set of fixed contacts 86 of the circuit selector 84. The brush arm 83 of this device is being now rotated by the 10 pulling of the handle through the segment 82, so that when said brush comes onto the live or two hour contact 86, the current passes thereto and therefrom to wire 110, through the magnet 111, and thence by wires 112, 113, back to battery.

As at this time and also by the movement of the handle the plate 70 is being raised synchronously with the movement of brush-arm 83, the plate 70 is checked at the proper 20 instant by the engagement therewith of a pawl 114, controlled by the magnet 111.

By the same movement of the brush arm 83, the current is also passed to the zero contact 85, through wire 115, to magnet 116, 25 which locks the plate 73 by means of a pawl 117, and hence the differential will set the hour type wheel 63 to print the numeral 2. The dogs 114 and 117 will be held in cooperation with the racks 70 and 73 by the inherent friction due to the upward pull of 30 the spring between members 68 and 69 and the downward pull of spring 76^a on arm 76. The spring connecting members 68 and 69 tends to pull rack 70 upward tightly 35 against dog 114 while spring 76^a acting on pinion 74 tends to pull rack 73 downward tightly against dog 117 and will hold these dogs in position until the parts of the machine are operated in reverse directions to 40 release this pressure. The relative timing of the movement of pins 92, 93 on the one hand and the switch arm 83 on the other is such that the contacts 92, 93 engage the plate 94 before the contacts 83^a, 83^b on switch arm 83 make contact with the first of the 45 contact points 85, 86.

If the corresponding circuits be traced with regard to the other circuit selector 84^a whose one tenth hour contact 86^a is alive, it 50 will be seen the magnet 118 locks the plate 70^a at the one tenth of an hour position, and magnet 118 will lock the other plate 73^b at the zero position, so that the differential will move the tenths of an hour type wheel 63 to the position where it will print 1. The card will, therefore, show 2 hours and 1 55 tenth of an hour as the elapsed time and will contain the holes 3, 4, 6 and 7.

At the finish of the next job the proper 60 pins 92, 93, will enter the holes 6 and 7, and the time which has elapsed since those holes were punched will be printed on the right hand margin of the card.

At any time the total of the elapsed time 65 printed on a card may be ascertained and

printed at the top of the card at 119, by the following means. In Fig. 1 a vertical push rod 120 is shown as mounted in the machine and normally held up by a spring 121. When a total is to be printed, this rod is 70 pushed down and a lever 122 connected to its lower end turns a shaft 123 and by such means shifts an arm 124 (Fig. 2) and thereby transfers the movable contacts 88 and 90 from contacts 87 and 89 to 89 and 91 respectively and transfers contacts 88^a, 90^a, from contacts 87^a, 89^a to contacts 89^a and 91^a respectively. 75

A bifurcated projection 125 on said rod 120 engages a pin on a pivoted lever 126 and 80 forces said lever down. This lever is connected by a link 127 with a pivoted lever 128 connected by a spring 129 with one side of a frame turning loosely on the center shaft 130. The two sides of this frame are designated 131, and are shown in Figs. 1 and 4. The free ends of the side levers 131 are pivotally connected by links 132 to the shaft 132^a that carries the two rows of pins 92 and 93, and tends to pull these pins down 90 as the push rod 120 descends.

Extending from the push rod 120 is an arm 133 (Fig. 20) to which the arm 22 is pivoted, and as the push rod descends this arm 22 is carried below the projection 134 on the knife 15, whereupon that knife is retracted by a spring 135 and the projection 16 thereon withdrawn from the chute and permits the inserted card to drop to the bottom of the chute. 100

The links 132 carry the device shown in Fig. 21, that is to say, a small spring actuated pawl 136, rigid with which is an arm 137 with a rounded end having a square shoulder. As the links are carried down 105 by the side bars 131, the arm 137 travels over the card, but as soon as it reaches the cut away portion of the same it swings to the right and permits the pawl 136 to engage in a tooth or step in a fixed plate 138 and arrests the downward movement of the pins 92 and 93 and the side bars 131. 110

Another function performed by the push rod 120 is to bring a pin 139 thereon into engagement with a pivoted arm 140 which is fast to the shaft 141, carrying the pins 95 and 96. Whereby, on the descent of the said rod these pins will be swung over toward the card and will pass through any holes therein with which they may register. 115

Keeping now in mind the construction of the parts described, it will be seen that when a total is taken, the lower pins 95, 96, enter the starting holes, while the upper pins 92, 93, enter the last or upper holes, these 125 springs having been lowered and stopped in the proper position to do this. It will also be observed that the contacts 88 and 90 and 88^a and 90^a have been shifted, so that if we assume these conditions and again refer to 130

the diagram, Fig. 26, the operation of total printing will be readily understood.

The pins 95, in other words, will now be connected through contacts 90 with contacts 85 on the left hand side of the circuit selector 84, while the pins 93 will be connected through contacts 88 with contacts 86 on the right hand side of circuit selector 84. In similar manner pins 96 will be connected by contacts 90^a with the left hand contacts 85^a of circuit selector 84^a and pins 92 with the right hand contacts 86^a of the same selector through contacts 89^a.

In all other respects the operation is the same as that hereinbefore described except, of course, that the printed time will be the total clock time between the first punching and the last punching of the card, without reference to the number of intermediate 20 punchings.

As stated above, much of the mechanism employed in this device is familiar to those skilled in this art and is not therefore described in great detail. This is particularly true of the differential, which, in practice, would be supplied with the usual accessories, and which is a mechanism now well understood, it being, for example, fully set forth in U. S. Patent No. 1,267,510, to J. W. Bryce, dated May 28, 1918, and U. S. Patent Number 1,186,541 to J. W. Bryce, dated June 13, 1916.

In summarizing the operation of the machine, it will be noted that when the several operations are performed upon the card to compute the time consumed on each job, the pins 92, 93 cooperate with the card to ascertain the positions of the last previous perforations and according to the positions 40 of such perforations energize a corresponding one of contacts 85 in the selector 84 and a corresponding one of contacts 85^a in selector 84^a. At this time timing mechanism through the sunflowers 56, 57 will energize one of the contacts 86 of selector 84 and one of contacts 86^a of selector 84^a. In this way the last previous perforations in the card will control the plates 73 and 73^b and the current time will control the positioning 50 of plates 70 and 70^a. This in turn as we have seen controls the setting of the type wheels 63, Fig. 7. When on the other hand the total time represented by all jobs recorded on the card is to be computed the operation of the rod 120 Fig. 1, throws the sunflowers 56, 57 representing the clock timing, out of control and at the same time brings the contacts 95, 96, Fig. 2 into operation. The card is dropped to the bottom 60 of its slot so that contacts 95, 96 cooperate with the first perforations made in the card. The upper contact pins 92, 93 at this time are brought into cooperation with the uppermost set of perforations in the card. Under these conditions contact pins 95 and 96

determine which of contacts 85 and 85^a of selectors 84, 84^a shall be energized while the contact pins 93, 92 determine which of contacts 86, 86^a of selectors 84, 84^a shall be energized. Thus it will be seen that the first holes perforated through the card will control the positioning of plates 73 and 73^b while the last set of holes made in the card control the positioning of plates 70 and 70^a so that the positioning of the type wheels 75 63 is determined by the difference in the positioning of the first and last sets of perforations made in the card, irrespective of the current time.

This device is of very substantial value as a means of saving material and time. It being purely automatic in its operation, it obviates the necessity of mental computations and in this regard is a great labor saver.

What I claim as my invention is:—

1. In a recording mechanism of the kind herein described, the combination with timing mechanism, manually manipulative mechanism and time controlled card punching means, of time type wheels and printing mechanism, means for setting said type wheels and cooperating circuit controlling mechanism therefor the operation of which is dependent upon and controlled by the timing mechanism, the punched holes in the card and also by the manual mechanism whereby the elapsed time between one punching and the next will be printed upon the card.

2. In a recording mechanism of the kind described adapted to punch and print a card at varying intervals, as for example at the beginning and ending of certain jobs, of time controlled punching mechanism and 105 time printing mechanism and means for setting the latter dependent upon the length of the intervals between successive punchings whereby the elapsed time only between such punchings will be printed.

3. In a recording mechanism of the kind described adapted to punch and print a card at varying intervals, as for example, at the beginning and ending of certain jobs, of time controlled punching mechanisms, time 115 printing mechanism and means for adjusting the machine so as to cause the printing mechanism at will to record the total elapsed time between the initial and the final punching operations.

4. In a recording mechanism of the kind described the combination with time controlled card punching mechanisms of time controlled circuit closers in circuits adapted to be completed through punched holes in the card, of circuit selectors operated by the power applied to operate the machine and time printing mechanism controlled by the conjoint action of the time controlled circuit closer and the power operated circuit 130

selectors, whereby the elapsed time between the punchings will be printed.

5. In a recording mechanism of the kind described, the combination of the following instrumentalities, a time controlled card punching mechanism, a time controlled circuit controller, pins adapted to close circuits by passing through holes in a card, circuit selectors operated by the manually operated punching and printing mechanism, circuit connections between the circuit controller, the pins and the circuit selectors, time type wheels adapted to be set by the cooperative action of the said mechanisms and means for printing from the type so set on an inverted card the elapsed time between successive punchings.

6. In a recording mechanism of the kind described, the combination with time controlled card punching mechanism, time printing mechanism, means for printing thereby the elapsed time between each two of a greater number of successive punchings dependent for operation upon the duration of such periods, and means similarly controlled for printing the total elapsed time between the initial punching and the last of any number of punchings.

7. In a recording mechanism of the kind described, the combination with time controlled card punching mechanism, time printing mechanism, and means dependent upon the length of the interval between successive punchings for setting such printing mechanism to print such elapsed time, of a total elapsed time printing controlling means, comprising supplemental contact pins adapted to register with the holes initially punched in the card, means for moving the original contact pins to register with the holes last punched in the card and circuit controlling means and connections whereby the printing mechanism is caused to print the

elapsed time between the initial and the final punchings.

8. In a recording mechanism of the kind described, the combination of time controlled card punching mechanism, time printing wheels, an operating handle for operating the punching mechanism and setting the time type wheels, time controlled circuit controllers, circuit selectors operated by the movement of the handle, contact pins adapted to pass through registering holes in the card, circuit connectors between the circuit controllers, the pins, and the circuit selectors and electro-magnets therein for determining the extent of movement of the type wheels, whereby they are set to print the elapsed time between successive punchings.

9. In an elapsed time recording device, time controlled means for computing and recording on a card elapsed time for a plurality of jobs, and means controlled by such records for recording the total of the several elapsed time records contained on such card.

10. In an elapsed time recording device, time controlled means for computing and recording on a card elapsed time for a plurality of jobs, and means controlled by such records for recording on the same card the total of the several elapsed time records contained on such card.

11. In a recording machine, time controlled record effecting means whereby designations of the relative starting and finishing times of a plurality of jobs may be effected upon a single card, means controlled by the card for automatically printing the time consumed on each job, and means for printing upon the card the total time consumed on all jobs represented thereon.

In testimony whereof I hereto affix my signature.

JAMES W. BRYCE.
